UNITED STATES PATENT OFFICE

1,991,560

CASH REGISTER

Leo G. A. Kömmling, Berlin, Germany, assignor
to The National Cash Register Company, Dayton, Ohio, a corporation of Maryland

Application January 30, 1931, Serial No. 512,255

13 Claims. (Cl. 235—3)

This invention relates to cash registers and the like, and particularly of the type shown in United States Letters Patents, Nos. 751,611 and 773,053, granted to Thomas Carroll on February 9, 1904 and October 25, 1904, respectively.

Machines of the type shown in the above named patents are provided with levers adapted to be differentially positioned to set up amounts and various other data, which levers differentially 10 position totalizer actuators. After the totalizer actuators are thus positioned by the levers, the totalizer is moved into engagement therewith, and then moved relatively thereto, so that the amount set up in the actuators is entered into 15 the totalizer, after which the same is disengaged.

The printing mechanism in machines of the type disclosed in the above mentioned patents is usually located at the left side thereof, the type being set under control of the actuating racks in 20 the manner fully described in said patents. Such printing devices may be arranged to print and issue checks or to print upon insertable slips or cards as desired.

In the present embodiment the printer is controlled to take either two impressions during an 25 operation of the machine, or none at all. The two impressions may be made on one card or on two separate cards.

It is in connection with a machine having a 30 printer adapted to print upon one or more inserted cards, that the present invention is associated. When printing on a plurality of cards during a single operation it is sometimes necessary to print upon different lines, remotely 35 spaced from one another on those cards, that is, it may be desirable to print upon line 2 of the first card and line 8 of the second card. Under these conditions it is quite difficult to provide a feeding device for the second card that will feed 40 it the distance required after the first card has been printed upon, and therefore, it becomes necessary to shift the second card to the proper line by hand, and since the speed at which the machine operates prohibits the manual withdrawal 45 of the first card and the proper insertion of the second card during the machine cycle, a novel means has been provided to interrupt the operation of the machine after the imprint has been made on the first card.

50 One type of interrupting device is shown in United States Letters Patent, No. 1,658,993, granted to L. G. A. Kömmling on February 14, 1928.

In the machine shown in this latter patent, 55 there are two motor bars provided, one to re-

lease the machine at the beginning of an operation, and one to release the machine after the machine has been stopped, so that it may complete its operation.

It is an object of the present invention to provide a machine of the type shown in the two Carroll patents above mentioned with two totalizers interspersed one with the other in place of the single totalizer shown in the above mentioned 5 patents.

It is also an object to provide a mechanism under the control of an adjustable manipulative device to select one or the other of the totalizers for operation.

It is a further object of the present invention 15 to provide novel means, under control of the totalizer selecting mechanism to control an interrupting device for the main operating drive of the machine, so that the machine can be stopped after the impression has been made on one printing 20 medium, so as to allow the operator to position a second printing medium to print on any desired line thereon.

It is a further object of the present invention 25 to control a consecutive number actuating device driving mechanism so that it will be rendered ineffective during certain operations depending upon which of the totalizers has been selected for operation.

With these and incidental objects in view, the 30 invention includes certain novel features of construction and combinations of parts, the essential elements of which are set forth in appended claims and a preferred form or embodiment of which is hereinafter described with reference to 35 the drawings which accompany and form a part of this specification.

In the drawings:

Fig. 1 is a side elevation of applicant's novel 40 controlling devices shown in their normal positions.

Fig. 2 is a detail showing a portion of the device for controlling a consecutive number actuating device driving mechanism.

Fig. 3 is a side elevation of a part of the mechanism shown in Fig. 1, but with the parts in their 45 moved positions.

Fig. 4 is a view of the mechanism shown in Fig. 2 with the parts in their moved positions.

Fig. 5 is a front view of the device with the 50 totalizers shown in a position whereby the right-hand totalizer is in position to be operated.

Fig. 6 is a cross section through the machine showing the type of machine to which the present invention is shown applied.

IN GENERAL

Generally speaking, the shifting of the totalizers into and out of cooperative relation with the actuators is used to control and determine 5 the kind of an operation through which the machine will go, that is, whether or not that operation will be interrupted before the machine completes one complete cycle. When a certain one of the totalizers is selected, in this specific case 10 the right-hand one, the machine is interrupted after it completes about one-half of its cycle to allow the operator to adjust record material to receive a printing impression upon the line desired. When the left-hand totalizer is selected, 15 the machine goes through a complete cycle without any interruption whatsoever.

The two totalizers shown in Fig. 5 are interspersed, the first, third and fifth wheels, beginning at the right, belonging to one totalizer; and 20 the second, fourth and sixth wheels, beginning at the right, belonging to the other totalizer, the latter being one which is not adapted to be reset to zero, and the former being adapted to be restored to zero at the will of the operator. In 25 other words, the right-hand totalizer is a subtotalizer, and the left-hand totalizer is a grand totalizer.

The selection of the totalizer to be operated, in addition to determining whether or not the 30 machine will be interrupted during its operation, also controls the actuation of a consecutive numbering device.

DETAILED DESCRIPTION

35 *Keyboard and differential mechanism*

The keyboard and differential mechanisms of the machine to which the present invention is shown applied are not illustrated, nor will they be described in the instant case, since they are 40 substantially identical with the keyboard and differential mechanisms shown in the two Carroll patents previously mentioned, and reference is to be made to these patents for a general understanding of the type of machine with which applicant's invention is associated.

45 *Totalizer*

Each of the above mentioned patents discloses a single totalizer, but, as previously stated, in the 50 present invention applicant uses two totalizers which he has interspersed one with the other, they being of the same general type as is shown in the Carroll patents. Fig. 6 shows a cross section of the Carroll type of machine with the necessary modifications of the totalizer illustrated. It is, therefore, not thought necessary to go into any detailed description of the totalizers, and they will be somewhat briefly referred to.

The interspersed totalizers include adding 60 wheels 12 (Figs. 5 and 6) and 13 (Fig. 5) arranged in groups corresponding to the value of the respective denominational orders. These wheels are carried upon a shaft 11 journaled in a totalizer frame 14, which is guided to move in bars 15 pivoted in the machine frame, in the manner that bars 122 are pivoted in frame 34 of the Carroll Patent 751,611, illustrated in Figs 1 and 2 of said patent.

70 All adding wheels 12 and 13 are arranged in a laterally shiftable frame 16, which frame is shifted relatively to the pivoted frame 15.

Totalizer shifting mechanism

The means for shifting the totalizers laterally 75 for selecting purposes will now be described.

Connected to the laterally shiftable frame 16 (Figs. 5 and 6) is a rod 17 carrying a pin or roller 18 entered in a slot of a shiftable slide 19. This slide has cam slots 20 and 21 at its upper and lower ends, respectively, by means of which slots it is shiftable guided by pins 22 and 23 mounted in the machine frame (not shown).

Upon the movement of a special selecting lever 5 or key 90 and rack 25, the frame 16 is moved laterally in such a way that the adding wheels 10 12 or the wheels 13 are brought into cooperative engagement with the differential mechanism of the machine. With the parts in the positions shown in Fig. 5, the adding wheels 12 are in 15 cooperative relation with the differential mechanism, and the pins 22 and 23 occupy the upper ends of the slots 20 and 21.

When the adding wheels 13 are selected for operation, the slide 19 is moved upwardly in a manner to be hereinafter described, and the pins 20 22 and 23 occupy the lower ends of the slots 20 and 21. Due to the shapes of the slots 20 and 21, when the slide 19 is moved upwardly, it is also moved to the left, as viewed in Fig. 5, which movement through the rod 17 shifts the totalizer 25 frame 16 into such a position that the adding wheels 13 will be in position to be actuated.

The slide 19 is provided with a stud 24 (Fig. 5) entered into a fork of a vertically reciprocable rack 25 (Figs. 1 and 3) having teeth at its lower 30 end meshing with teeth of a disk 26 rotatably mounted upon a shaft 27. The disk 26 may have secured thereto a manipulative lever 90 (Fig. 1). This lever 90 is used to select one of the two totalizers 12 or 13 for operation. Movement of 35 the lever clockwise from the position shown in Fig. 1, rotates the disk 26 clockwise and raises the rack 25, whereupon the pin 24 raises the slide 19 to shift the totalizer frame 16 toward the left as viewed in Fig. 5, as previously described.

Movement of the lever 90 back to its normal position lowers the rack 25, whereupon the stud 14 lowers the slide 19 to the position shown in Fig. 5, thus moving the totalizer frame 16 back to the position shown in Fig. 5, in which position 45 the totalizer wheels 12 are in position to be operated by the actuator.

Machine drive and interrupting means

The main drive shaft of the machine is shown 50 at 36, Fig. 1, and may be operated manually by driving handles, such as shown in both of the Carroll patents previously mentioned, or in any other suitable manner. This drive shaft has means associated therewith to arrest its movement at the completion of one 360 degree cycle, and also mechanism associated therewith to interrupt or arrest its movement prior to the completion of said 360 degree cycle, depending entirely upon the totalizer selection. Such 60 mechanism will now be described.

The rack 25 has secured thereto a bracket 28 (Figs. 1, 3, 5 and 6) having a large notch cooperating with a pin carried by a bell crank 29 pivoted at 80 (Figs. 5 and 6) to the machine frame. 65 This bell crank 29 also carries a pin 30 cooperating with the annular groove of a collar 31 secured to a shiftable shaft 32.

Also secured to this shaft 32 is an arm 33, the upper end of which normally lies in the path of 70 movement of a long pin 35 carried by a gear 34 secured to the drive shaft 36.

When the rack 25 is raised by movement of the lever 90 in the manner previously described, the lower edge of the notch in the bracket 28, by its 75

cooperation with the pin in the bell crank 29, rocks the bell crank clockwise, whereupon the pin 30 shifts the shaft 32 and arm 33 to the left as viewed in Fig. 5. After the arm 33 has been shifted as just described, its upper end also lies in the path of movement of a shorter pin 37 carried by the gear 34.

This gear 34 has secured thereto arresting plates 38 and 38', one being appropriate to each pin 35 and 37. Cooperating with these disks is a pawl 39 carrying a pin 40 engaging a slot in the arm 33. The pawl 39 has connected thereto a spring 42 tending to rock it counter-clockwise, as viewed in Fig. 1, and the arm 33 has connected thereto a spring 43 tending to swing it counter-clockwise.

When the shaft 36 is turned counter-clockwise by means of an operating handle, such as shown in the Carroll patents above mentioned, or any other suitable means such as a motor, it is adapted to receive one full rotation for each operation of the machine.

When the rack 25 is occupying the position shown in Figs. 1 and 3, wherein the adding wheels 12 are in position for registering amounts received, the arm 33 (Fig. 5) is in the path of the long pin 35 only, it being held out of the path of the shorter pin 37 by the bracket 28.

When the parts are in these positions the shaft 36 is permitted to complete one 360 degree cycle of movement. Near the end of this movement the long stud 35 strikes the upper end of the arm 33 and rocks it clockwise against the tension of the spring 43. This clockwise movement of the arm 33 through the pin 40 carries the pawl 39 clockwise against the tension of its spring 42 into a position whereby the nose of the pawl 39 will be in the path of a shoulder of the arresting plate 38, whereupon as the shaft 36 completes its movement said shoulder, by its contact with the end of the pawl 39, stops the shaft 36 in its normal home position. Substantially at the time the cycle of operation is completed the stud 35 passes off the end of the arm 33, whereupon the latter is returned to the position shown in Fig. 1 by its spring 43, but the pawl 39 remains in its effective retaining position.

When an operation of the same kind is to be started again it is necessary, as is well known in the art, to give the shaft 36 a slight reverse or clockwise motion just sufficient to disengage the plate 38 from the pawl 39, whereupon the spring 42 moves the pawl counter-clockwise into an ineffective position.

When, however, the proprietor of the establishment is collecting items, such as savings, which amounts are not to be accumulated upon the department totalizer 12, it is desirable to print multiple records in duplicate. For this reason the totalizer 12 is shifted to an ineffective position and the totalizer 13 brought into an effective position in the manner previously described by the movement of the selecting lever 90.

It has also been described how the movement of the lever 90 clockwise, as viewed in Fig. 1, through the disk 26, rack 25, bracket 28, bell crank 29, and shaft 32, shifts the arm 33 to the left, as viewed in Fig. 5, to bring its upper end into the path of movement of the stud 37 as well as the stud 35. With the parts in these positions, that is, with the arm 33 in the path of movement of the studs 35 and 37, upon the counter-clockwise movement of the shaft 36 and gear 34 the stud 37 will contact the upper end of the arm 33 and move it clockwise when the shaft 36 has completed only about one-half its movement. The

clockwise movement of the arm 33 at this time, through the stud 40, rocks the pawl 39 clockwise, whereby its upper end is in the path of a shoulder on the arresting disk 38', and consequently, the movement of the shaft 36 is interrupted or arrested at this point in the operation.

During the first half of this movement of the shaft 36, the printing mechanism to be later described is operated to effect an impression upon one record material. After the interruption of the shaft 36 occurs, the operator may remove the first record material and position a second record material to receive an impression during the second half of the operation of the shaft 36. After the new record material has been properly placed in the machine, the shaft 36 is rotated slightly clockwise to allow the pawl 39 to become disengaged from the shoulder of the disk 38', after which the counter-clockwise movement of the shaft 36 may be completed. Near its completion the pin 35 functions in connection with the arm 33 to stop the machine at the end of the operation, in the manner previously described.

Printing devices

The printing hammer is adapted to be latched against operation during the uninterrupted operations so that no impressions are made during such operations. When the machine is set to make interrupted operations, the printing hammer is released to permit it to take two impressions from the type carriers during the interrupted operations.

A hammer 45 adapted to print from type wheels 85 (Fig. 1) is rotatably mounted upon a shaft 44. The hammer carries a stud 48 which rests against a bell crank 46 rotatably mounted upon the shaft 44. One arm of the bell crank is held in contact with a cam 49 by a strong spring 47. This cam 49 is secured to a shaft 50 rotated by gearing (not shown) driven from the gear 34. The cam 49 has two risers and two abrupt shoulders, whereby the hammer 45 may be cocked and released twice during each complete cycle of operation, the spring 47 effecting a rapid counter-clockwise movement of the hammer as the end of the bell crank 46 passes the abrupt shoulders.

The disk 26 is provided with a second set of teeth 51 meshing with a segment 52 secured to a shaft 53. Also secured to the shaft 53 is an arm 54 carrying a stud 55 projecting into a cam slot 56 of an arm 58 secured to shaft 57. Also secured to the shaft 57 is a bell crank 59 carrying a spring actuated locking pawl 60 which cooperates with a hammer 45 to prevent the operation thereof during uninterrupted operations in a manner to be presently pointed out.

When the totalizer selecting lever 90 is moved clockwise (Fig. 1), the teeth 51 rock the segment 52, shaft 53, and arm 54 counter-clockwise, whereupon the stud 55 rocks the arm 58 and shaft 57 counter-clockwise, thus removing the pawl 60 from its cooperative relation with the hammer 45.

During the cycle of operation, which is uninterrupted, the shaft 53, arm 54 and stud 55 occupy the positions shown in Fig. 1, which holds the arm 58 and bell crank 59 in a position whereby the pawl 60 is retaining the hammer 45 in the position shown, so that the same cannot be rocked against the type wheels 85 during such an operation.

The bell crank 59 is connected by a link 61 with an arm 62 pivoted upon a shaft 63. This arm 62 has a slot into which projects a pin 64 of a link 65 pivoted to a rocker arm 66 loosely mounted upon

the shaft 53. This arm 66 is adapted to carry a consecutive counter actuating pawl (not shown).

When the parts are in the positions shown in Fig. 1, the pin 64 is resting in a slot or recess 68 in a stationary framework 86 shown by dot-and-dash lines in Figs. 1, 2 and 4. When the pin 64 is in this position the consecutive counter actuating driving rocker arm 66 is disabled, so that during the operation of the machine the consecutive 10 number wheels will not be operated.

However, when the parts occupy the positions shown in Fig. 4, in which the arm 62 has been raised by movement of the bell crank 59, the pin 64 then lies in a notch 69 of a pitman 70 adapted 15 to be reciprocated by a cam disk 71 (Fig. 2) secured to the drive shaft 36. During the reciprocatory movement of the pitman 70 the rocker arm 66 is rocked about the shaft 63 through the medium of the stud 64 and link 65 to effect an operation of a consecutive numbering device of the usual character (not shown).

Simultaneously with the locking of the printing hammer 45 by the pawl 60 in the manner previously described, the arm 62 is retained in the position shown in Fig. 1 by the link 61, wherein the stud 64 is retained in the recess 68 in the stationary frame 86, thus preventing any movement of the consecutive number actuating device driving arm 66.

30 The number of times which the machine is interrupted in the cycle depends wholly on the number of arresting plates 38' that are used.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which 40 follow.

What is claimed as new, is:

1. In a machine of the class described, the combination of a main operating device; means cooperating therewith to arrest said device upon completion of one cycle of movement thereof or prior thereto; a plurality of totalizers; means for selecting any one of said totalizers for operation; and mechanism controlled by an element of the last-mentioned means to control a part of the arresting means for interrupting the movement of the main operating device prior to the completion of its full cycle of movement.

2. In a machine of the class described, the combination of a main operating device; means cooperating therewith to arrest said device upon the completion of one cycle of movement thereof or prior thereto; a plurality of totalizers; means for selecting any one of the totalizers for operation; and mechanism controlled by an element of the last-mentioned means, for operating a part of the arresting means to interrupt the movement of the main operating device prior to the completion of its full cycle of movement.

3. In a machine of the class described, the combination of a main operating device; a plurality of totalizers; means for selecting any one of the totalizers for operation; an arresting device associated with the main operating device; a projection carried by the main operating device; a member connected to the arresting device and operated by the projection to move the arresting device into an effective position to arrest the main operating device upon the completion of one cycle of movement thereof; a second projection carried 75 by the main operating device; and means con-

trolled by the totalizer selecting means for moving said member into the path of movement of the second projection whereby the arresting device is moved into an effective position prior to the completion of its full cycle of movement.

4. In a machine of the class described, the combination of a main operating device; a plurality of totalizers; means for selecting any one of the totalizers for operation; means adapted to arrest the main operating device at the completion of its 10 full cycle of movement and at a time prior to the completion of its full cycle of movement; and a device connected to an element of the last mentioned means and controlled by the totalizer selecting means to operate said element.

5. In a machine of the class described, the combination of a main operating device; a plurality of totalizers; means for selecting any one of the totalizers for operation; an arresting device associated with the main operating device; and means 20 for causing the arresting device to stop the main operating device at the end of its full cycle said last named means controlled by the totalizer selecting means to also cause the arresting device to stop the main operating device at a time prior to 25 the completion of its full cycle depending upon the totalizer selected.

6. In a machine of the class described, the combination of a main operating device; a plurality of totalizers; means for selecting any one of the 30 totalizers for operation; an arresting device associated with the main operating device; a plurality of members carried by the main operating device, one member adapted to contact the arresting device to stop the main operating device prior to the 35 completion of its full cycle, and another of said members adapted to contact the arresting device at the end of its cycle; and means controlled by the totalizer selecting means for determining the effectiveness of the arresting device relatively to 40 the stopping of the main operating device prior to the completion of its cycle.

7. In a machine of the class described, the combination of a main operating device; a plurality of totalizers; means for selecting any one of 45 the totalizers for operation; an arresting device associated with the main operating device; a plurality of projections carried by the main operating device; a laterally shiftable member adapted to be operated by one or all of said projections to actuate the arresting device; and means intermediate the totalizer selecting means and said laterally shiftable member for determining whether one or all of said projections shall operate said member.

8. In a machine of the class described, the combination of a main operating device; a plurality of totalizers; means for selecting any one of the totalizers for operation; an arresting device associated with the main operating device; a plurality of members carried by the main operating device; an adjustable means adapted to be operated by one or both of said members; means under control of the totalizer selecting means for determining whether one or both of said members shall operate the adjustable means; and means intermediate the adjustable means and the arresting device for actuating the latter upon operation of the former.

9. In a machine of the class described, the combination of a main operating device; a plurality of totalizers; means for selecting any one of the totalizers for operation; an arresting device associated with the main operating device; a plurality of members carried by the main 70 device.

5 operating device and adapted to cooperate with the arresting device to stop the main operating device prior to and at the completion of its full cycle of movement; a plurality of projections carried by the main operating device; an adjustable member connected to the arresting device and adapted to be operated by all of said projections to move the arresting device into effective position relatively to the members carried by the 10 main operating device; and means intermediate the totalizer selecting means and the adjustable device and operated by the totalizer selecting means to shift the adjustable device into a position whereby only one of the projections can 15 operate the same.

10. In a machine of the class described, the combination of a main operating device; a plurality of totalizers; means for selecting any one of the totalizers for operation; an arresting device associated with the main operating device; means intermediate the arresting device and the main operating device to shift the arresting device into position to stop the main operating device at the completion of its cycle of movement; 20 a reciprocating member operated by the totalizer selecting means; a shiftable device carrying said intermediate means; and means intermediate the shiftable device and adapted to be operated by the reciprocating member to move the intermediate means into a position whereby the same 25 operates the arresting device to stop the main operating device prior to the completion of its full cycle of movement.

11. In a machine of the class described, the combination of a plurality of totalizers; means for selecting any one of the totalizers for operation; printing elements; impression means; means for retaining the impression means in an ineffective position; a lever carrying said retaining means; a rockable driving member; means connected to the driving member and adapted to retain the same in an ineffective position; means intermediate the totalizer selecting means and said lever for operating the latter to release the 40 impression retaining means when the totalizer selecting means is moved into a certain position;

and means intermediate said lever and said driving member retaining means to release the driving member upon release of the impression means.

12. In a machine of the class described, the combination of a main operating device; a plurality of totalizers; means for selecting any one of the totalizers for operation; printing elements; impression means; a driving member; means for retaining the driving member in an ineffective position; means for retaining the impression means in an ineffective position; arresting means associated with the main operating device to stop the latter at the completion of its full cycle of movement; means operated by the totalizer selecting means for moving the main operating device 15 arresting means into a position to arrest the main operating device prior to the completion of its full cycle of movement when the totalizer selecting means is moved into a certain position; and means also operated by the totalizer selecting means when the latter is moved into said certain position for rendering the driving member retaining means and the impression retaining means ineffective when the main operating device is arrested prior to the completion of its move- 20 ment.

13. In a machine of the class described, the combination of a main operating device; an arresting device associated therewith and adapted to stop the operating device at the completion 30 of its full cycle of movement; a shiftable member associated with the arresting device to operate the same; a differentially adjustable device; and means intermediate the differentially adjustable device and the shiftable member, including a reciprocator means and a rockable member to shift the shiftable member into position to be operated to bring the arresting means into a zone wherein it is operated by the main operating device to interrupt the operation of the main 40 operating device prior to the completion of its cycle, upon movement of the reciprocator member by the differentially adjustable device when the latter is moved into a certain position.

45 LEO G. A. KÖMMLING.
